UNITED STATES PATENT OFFICE.

WINFIELD H. SOUTHDARD, OF PRESQUE ISLE, MAINE.

FLUE STOPPER.

Application filed June 16, 1926. Serial No. 116,485.

This invention appertains to new and useful improvements in flue opening stoppers and has particular reference to such a stopper designed primarily for closing the stove pipe opening in a chimney after the stove pipe has been removed therefrom.

An important object of the present invention is to provide an improved flue opening stopper of the above character which will be durable and efficient in use, one which will be simple and easy to manufacture and one which can be placed upon the market at a small cost.

Another object of the present invention is to provide such an improved flue opening stopper of the above character embodying a cylinder or thimble having inner and outer disks separated so as to provide an air space therebetween.

Another object of the present invention is the provision of such an improved flue opening stopper of the above character including a cylinder or thimble adapted to be inserted within the flue opening and having a stationary outer or cover disk and an inner disk disposed within the cylinder and spaced from the cover disk to provide an air space therebetween, said inner disk serving to prevent the heat from reaching the cover disk.

Numerous other objects and advantages of the present invention will become more readily apparent during the course of the following description when taken in connection with the accompanying drawings.

In the drawings forming a part of this application and wherein like characters of reference denote corresponding parts throughout the several views:

Figure 1 is a front view of a portion of a chimney showing a flue opening stopper associated therewith and constructed in accordance with the present invention.

Figure 2 is a side elevation of the improved flue opening stopper showing the same in position within the flue opening.

Figure 3 is a vertical sectional view taken on line 3—3 of Figure 1.

Referring now more particularly to the accompanying drawings wherein for the purpose of illustration has been disclosed a preferred embodiment of the present invention, the letter A generally indicates a portion of a conventional chimney having the usual flue opening 10 and B the present

improved stopper for closing the said flue opening after the stove pipe has been removed therefrom.

The stopper B embodies in its construction a cylinder or thimble 11 which is adapted to be inserted within the flue opening after the stove pipe has been removed therefrom, said cylinder being formed of a single length of material, the adjacent ends of which are secured together in any suitable manner such as by means of rivets or other fastening elements 12.

The outer end of the cylinder 11 is provided with the outwardly directed annular flange 13 and received over this flange is the inturned annular flange 14 formed on the outer or cover disk 15 which serves to close the outer end of the said cylinder.

The outer surface of the cylinder or thimble 11 is formed intermediate its ends with the circumferential groove 16, the provision of which results in the formation of a corresponding circumferential rib 17 on the inner surface of the said cylinder.

Received within the cylinder 11 and contacting with the circumferential rib 17 is a second or inner disk 18 provided with the annular peripheral flange 19 contacting with the inner surface of the cylinder 11. It will thus be seen that the circumferential rib 17 serves to retain the inner disk in spaced relation to the outer or cover disk so as to provide an air space therebetween. The inner disk 18 acts to prevent the heat within the chimney from reaching the cover disk 15 so that the provision of the air space between the outer and inner disks is an element of great safety.

The inner end of the cylinder 11 may be formed with diagonally disposed corrugations as indicated at 20 and as the cylinder is being inserted within the flue opening 10, these corrugations serve to scrape the wall thereof so as to remove therefrom any soot, dirt or the like which may have become attached thereto. Thus, the present device also acts to clean the wall of the flue opening as it is placed in position. The inner disk 18 may be firmly secured within the cylinder 11 or may be removably positioned therein as desired. Also, the inner portion of the cylinder 11 can be filled with cement or the like, if desired, thereby adding still greater safety to the stopper.

From the foregoing, it is believed that

the construction and use of the present invention will be readily appreciated and it is to be understood that changes in the details of construction may be resorted to without departing from or sacrificing the spirit of the invention so long as such changes fall within the scope of the appended claims.

What is claimed is:

- 10 1. In a stopper of the class described, a cylinder having an annular flange at its outer end, a cover disc having an inturned peripheral flange engaging over the flange of the cylinder, and diagonally disposed corrugations formed in said cylinder at the

inner end thereof, substantially as and for the purpose set forth.

2. In a stopper of the class described, a cylinder having an internal circumferential rib intermediate its ends, an annular flange at its outer end and diagonally disposed corrugations at its inner end, a cover disk having an inturned peripheral flange engaging over the flange of the cylinder, and a second disk positioned within the cylinder and held spaced from the cover disk by means of the said rib.

In testimony whereof I affix my signature.

WINFIELD H. SOUTHARD.
